UNITED STATES PATENT OFFICE.

MALCOLM CURRY, OF SCARSDALE, NEW YORK, AND STARR H. BARNUM, OF HAMDEN, CONNECTICUT.

OBSERVATION WINDOW FOR FURNACES.

1,417,976.

Specification of Letters Patent. Patented May 30, 1922.

Application filed October 27, 1921. Serial No. 510,908.

To all whom it may concern:

Be it known that we, MALCOLM CURRY, a citizen of the United States, and resident of Scarsdale, in the county of Westchester and State of New York, and STARR H. BARNUM, a citizen of the United States, and resident of Hamden, in the county of New Haven and State of Connecticut, have invented certain new and useful Improvements 10 in Observation Windows for Furnaces, of which the following is a specification.

This invention relates to improvements in observation windows for furnaces, and has for one of its objects to provide windows of 15 simple and inexpensive construction through which the fuel bed may be clearly seen without the observer being subjected to the direct heat and glare of the fire-box and without opening communication between the fire- 20 box and the outer atmosphere.

A further object of the invention is to provide simple and efficient means for preventing the transparent glare-eliminating panel of the window from becoming unduly heated 25 and preventing loss of heat during inspection of the fuel bed and influx of the outer atmosphere to the fire-box.

To the foregoing and other ends, which will hereinafter appear, the invention consists 30 in the features of construction, arrangements of parts, and combinations of devices set forth in the following description and particularly pointed out in the appended claims.

35 In the accompanying drawings, in which the preferred embodiment of the invention is illustrated,

Figure 1 is a front elevation of the window applied to the fire-box wall of a furnace;

Fig. 2 a side elevation thereof;

Fig. 3 a transverse section on the line 3—3 of Fig. 1;

Fig. 4 a perspective view of the sliding 45 frame;

Figs. 5 and 6 vertical sectional views on the line 5—5 of Fig. 1, showing the sliding frame in lowered and raised position, respectively; and

50 Fig. 7 a horizontal section on the line 7—7 of Fig. 1.

The furnace wall 10, which may be of any suitable construction, is provided with a peep-opening 11 at a point suitable for observing the fuel bed. As shown, the peep-

opening is rectangular in cross section, but it will be obvious that the shape and size of the opening may be varied, and may be formed with flaring sides as shown in the patent to Curry, No. 1,349,562, granted August 17th, 1920. While we prefer to provide the peep-opening in the brick wall of the furnace, as shown, it will be obvious that the opening may be formed in any suitable part of the furnace, and that the window 65 hereinafter described may be attached to furnace walls, casings, or doors of various construction provided with peep-openings

The metallic window frame or casing 12, which is of general rectangular box-like 70 form, is preferably cast in one piece, as shown, said frame being formed with a bolt flange 13 around its open inner end and being held against the outer side of the furnace wall over the peep-opening by bolts 14 and 75 nuts 15. The top, bottom and side edges of the frame are preferably offset from the corresponding edges of the peep-opening, as shown, so that the brick wall will be interposed between the edges of the frame and 80 the combustion chamber of the furnace to afford protection to the frame.

The outer end wall of the frame 12 is provided with a rectangular view opening 16 registering with the peep-opening 11, 85 and is formed with integral upturned lugs 17 along the lower edge of opening 16 and integral inwardly turned lugs 18 along the vertical edges of opening 16, said lugs 17 and 18 forming retaining means for a plate 90 19 of blue glass or other transparent glare-eliminating material. Plate 19 is loosely held against the front face of the frame 12 by the lugs, as shown, to permit expansion and contraction of the plate, and may be 95 readily inserted and removed for cleaning or renewal by a vertical sliding movement. The top and bottom walls of the frame 12 are provided with slots or openings 20 adjacent the front wall of the frame to permit 100 free circulation of air past the inner face of the glass plate 19 to assist in keeping said plate cool at all times.

A supplemental metal frame, preferably cast in one-piece, is slidable through the 105 main frame or casing 12. The slidable frame comprises side bars 21 loosely fitting in guideways or channels 22 formed in the imperforate side walls of the frame 12, a top cross-bar 23, a bottom cross-bar 24, and 110

an intermediate cross-bar 25. Said sliding frame is normally held by gravity in the position shown in Figs. 1, 2 and 5, in which position its downward movement is arrested 5 by the engagement of a continuous flange 26, formed around the upper edge of cross-bar 23, with the top wall of the frame 12. The top wall of the outer frame or casing 12 is formed with a rectangular slot 27, through 10 which the supplemental frame is slideable, and the bottom wall is formed with an internal recess or channel 28 in which the intermediate cross-bar seats when the parts are in the position shown in Figs. 1, 2, and 5. 15 The bottom wall of the casing 12 is provided with an I-shaped slot 29 to permit movement of the side bars 21 and bottom cross-bar 24 therethrough. The top cross-bar 23 is provided with a longitudinal slot 20 30 through which one or more panels or plates 31 of opaque non-combustible material which is also a non-conductor of heat, such as asbestos boards, are inserted in the upper section of the sliding frame, said asbestos plates 31 resting on bar 25 and being held in the frame by inwardly extending pairs of retaining flanges or ribs 32 formed on the side bars 21 of the frame between cross-bars 23 and 25. One of the side bars 30 21 of the sliding frame is provided with a vertical slot 33, extending between cross-bars 24 and 25, through which a sheet or plate 34 of transparent non-combustible or heat-resisting material, such as isinglass, is 35 slidably inserted in the lower half of the frame. The isinglass sheet 34 is retained in the sliding frame by pairs of lugs 35 formed on bars 21, 24 and 25. One side wall of casing 12 is slotted up from its lower edge at 40 36 to afford clearance for the insertion and removal of the isinglass sheet while the sliding frame is in its lowermost position. A suitable handle 37 has its upper end threaded through a lug 38 depending from the center 45 of cross-bar 24, and a lock nut 39 is provided for normally holding the handle against swinging movement. When the window is packed for shipment, the sliding frame may be slid partly up so as to register 50 with the flanged casing 12, and the handle 37 may be swung around over the casing after loosening the nut, thus forming a compact package.

It will be observed that when the parts 55 are in the position shown in Figs. 1, 2, 3 and 5 bars 25 and 23 close slots 29 and 27 so that there can be no substantial loss of heat therethrough, while the asbestos boards 31 prevent inward or outward passage of air 60 through the sliding frame and shield the blue glass plate 19 from heat radiating through the peep-opening 11 and also from flame, hot gases and soot. When the sliding frame is raised by pushing up on handle 37, 65 the asbestos boards are moved out of register

with the peep-opening and the sheet of isinglass is moved between the peep-opening and the blue glass panel to shield the glass panel and permit observation of the fuel bed. When the parts are in raised position it will 70 be observed that the isinglass sheet and cross-bars 24 and 25 will prevent loss of heat or the influx of cold air through the peep-opening, the bar 25 closing slot 27 and bar 24 closing slot 29. The handle 37 engages 75 the bottom wall of casing 12 to arrest the sliding frame in the position shown in Fig. 6.

It will also be observed that it is impossible to accidentally leave the sliding frame in raised position as it will drop down when 80 handle 37 is released. In the down position of the sliding frame the isinglass sheet is not exposed to smoke and soot and the glass plate 19 is more effectively protected from the heat of the furnace by the heavy non-heat-conducting asbestos boards. It will 85 also be observed that the sheets or plates 19, 31 and 34 may be readily inserted and removed for renewal or cleaning by a direct sliding movement and that simple means 90 are provided for holding said sheets or plates in place, said means requiring no manipulation.

What we claim is:

1. The combination with a furnace having 95 a peep-opening, of means for supporting a panel of transparent glare-eliminating material outside of the furnace in line with said opening, a support slideable transversely of the line of vision through said transparent panel and opening, and panels of heat-resisting material carried by said slideable support and movable therewith to alternately close the peep-opening, one of said heat-resisting panels being transparent and the other being 100 formed of material which is a non-conductor of heat.

2. The combination with a furnace having 110 a peep-opening, of means for supporting a plate of blue glass spaced from the outer end of the peep-opening, a sliding frame held to said supporting means between the furnace and glass plate transversely of the line of vision, and an asbestos plate and a sheet of isinglass carried by said frame and movable alternately between the peep-opening and glass plate when said frame is shifted in opposite directions.

3. An observation window for furnaces comprising a casing, a panel of transparent glare-eliminating material extending transversely of the casing, a frame slideable transversely of the casing at one side of the glare-eliminating panel, and a panel of heat-non-conducting material and a panel of transparent heat-resisting material carried by the frame and movable therewith to alternately close communication between one end of the casing and the panel of glare-eliminating material.

4. An observation window for furnaces comprising a casing, a panel of transparent glare-eliminating material extending transversely of the casing, a frame slidable transversely of the casing at one side of the glare-eliminating panel, and a panel of heat-non-conducting material and a panel of transparent heat-resisting material carried by the frame and movable therewith to alternately 5 close communication between one end of the casing and the panel of glare-eliminating material, said casing being provided with openings permitting free circulation of air between the glare-eliminating panel and the 10 panels on the sliding frame.
5. An observation window for furnaces, comprising a casing, a panel of transparent glare-eliminating material extending transversely of the casing, a vertically slidable frame extending transversely of the casing, a panel of heat-non-conducting material held in the upper portion of said frame, and a panel of transparent heat-resisting material held in the lower portion of the frame, said 20 last two panels being movable with the frame to alternately register with the first panel.
6. An observation window for furnaces, comprising a casing, a panel of transparent glare-eliminating material extending transversely of the casing, a vertically slidable frame extending transversely of the casing, a panel of heat-non-conducting material held in the upper portion of said frame, a panel 30 of transparent heat-resisting material held in the lower portion of the frame, said last two panels being movable with the frame to alternately register with the first panel, means for limiting the downward movement 35 of the frame, and a handle connected with the frame for shifting the frame upwardly.
7. An observation window for furnaces comprising a panel of transparent glare-eliminating material, means for supporting 45 said panel on a furnace spaced from the outer side of the furnace, and a shield slidably held to said supporting means to move transversely of the line of vision through the 50 panel of glare-eliminating material, said shield having a transparent portion movable into and out of the line of vision.
8. An observation window for furnaces, comprising a casing adapted for connection at its inner end to a furnace at a peep-opening, a panel of transparent glare-eliminating material extending transversely of the casing, and a panel of heat non-conducting material slidably supported on the casing and shiftable transversely of the casing between the inner end of said casing and the 55 panel of glare-eliminating material, said non-conducting panel in one position thereof closing communication between the inner end of the casing and the glare-eliminating panel. 60
9. The combination with a furnace having a peep-opening of a casing attached at one end to the outer side of the furnace at the peep-opening, a panel of transparent glare-eliminating material extending transversely 65 of the casing in the line of vision through the peep-opening, and a heat-resisting shield slidable transversely through the casing between the peep-opening and glare-eliminating panel and closing communication between 70 said opening and panel at all times, said shield having a transparent portion movable into and out of the line of vision, and said casing being provided with openings between said shield and panel communicating with the outer air. 75
10. The combination with a furnace having a peep-opening, of a casing attached at its inner end to the furnace at said opening, a panel of transparent glare-eliminating material extending transversely of the casing in the line of vision through the peep-opening, and a shield slidable transversely of the casing between said panel and opening and closing communication therebetween at all 80 times, said shield having a panel of heat-non-conducting material and a panel of transparent heat-resisting material shiftable alternately between the peep-opening and the glare-eliminating panel, and said casing 85 having openings therein between the shield and glare-eliminating panel communicating with the outer air. 90

In testimony whereof we hereunto affix our signatures.

MALCOLM CURRY.
STARR H. BARNUM.
